CLAIM

The ornamental design for a portion of a connector, as shown and described.

DESCRIPTION

FIG. 1 is a perspective view of a first embodiment of a portion of a connector showing my new design;

FIG. 2 is a front elevational view thereof;

FIG. 3 is a perspective view of a second embodiment of a portion of a connector showing my new design; and,

FIG. 4 is a front elevational view of the embodiment of FIG. 3.

The body portions of the connector shown in broken lines are for illustrative purposes only and form no part of the claimed design.
